DIFFUSER TUBE

Carl H. Nordell, Palm Springs, Calif.

Application February 26, 1947, Serial No. 730,931

8 Claims. (Cl. 261—121)

1

This invention relates to a diffuser tube used for the aeration of liquid or for the dispersion of gases or vapors therein and, more particularly, to such aerators or diffusers into which the air or gas is supplied under pressure, and passes into the liquid through orifices provided for that purpose. Such diffusers are employed in the activated sludge process of treating sewage, ore flotation processes, treatment of industrial wastes, and various fermentation processes, for example, for the manufacture of yeast and penicillin, and certain chemical processes where gas-liquid contact is essential.

Although many types of materials have been used in the fabrication of porous diffusers, few have been efficient to an extent to warrant wide commercial use, and these generally have not been entirely satisfactory in use. One type of porous diffuser of the prior art, which proved impractical, was made of porous wood. Another type that found little use commercially, was made by pulling a slitted or needled-punctured rubber sleeve over a perforated, thick metal pipe. This type of diffuser proved to be impractical because of the weight thereof, and because of the very large and costly head losses developed in forcing the air through the normally closed openings in the rubber sleeve.

The most commonly used tubular air diffusers of the prior art are made of porous carbon and ceramic material, both natural and artificial. These carbon and ceramic tubular diffusers have been generally formed of packed granular material with the grains bonded to one another by cementing or sintering, the voids between the grains forming irregular passages for the emission of gases. These porous tubes are of uncertain and non-uniform structure, and the resulting diffusion is necessarily likewise uncertain and non-uniform. The passages through these media are haphazard and tortuous and, for the sake of strength, there must be considerable thickness. In consequence, the diffusers are heavy and the air passages therethrough are very long relative to the diameter thereof. Considerable pressure is required to force the air or gas through the tortuous passages and the passages clog easily, either from dust in the air, particles of scale, or rust from the air main. Additionally, pore clogging in the ceramic tube is caused when the air supply is cut off, and the surrounding liquid backflows through the minute passages, carrying with it bits of debris that are not initially removed when the flow of air is resumed.

Another method of forming diffuser tubes that has found some usage has been to wind cord or rope in a plurality of layers around a perforated metal tube, the diffusion occurring as a result of the partial stoppage of the holes in the forami-

2

nous core, and the chance labyrinth of passages formed between the coils and through the rope. The high head loss and the unsatisfactory character of the diffusion were the main factors responsible for the impracticality of this diffuser tube. Another method of forming diffuser tubes which have proven to be impractical is to wind wire of circular cross section around a foraminated heavy metal tube.

I have discovered that the defects and objections inherent in the prior art porous tubular diffusers are minimized and substantially eliminated by wrapping a cord of non-circular cross section around a rigid, relatively light weight, hollow core, providing that but one layer of wrapping is used and the coils tightly pressed together. The hollow core is fabricated in a form in which flutes or corrugations are formed longitudinally across this core. In the valleys of the corrugations or flutes, there are orifices for controlling the passage of air from the core to the air spaces under the cord windings. The cord that is used for winding around the hollow metal cores possesses helical grooves so that when adjacent coils are pressed tightly together, the grooves form minute slanting passages or pores of substantially uniform character and dimensions for the emission of air or gas. This form of cord can be formed by extruding a plastic or by twisting two, three or more strands of textile or plastic cord into a cord of the desired thickness, in the same manner that a rope is formed. It is obvious that the size and spacing of the pores can be closely and positively controlled by selection of a cord of a desired size and by the tightness and compression of the winding.

The cord-wound diffuser of the invention, i. e., the fluted foraminated core and the winding, are fabricated from materials that are capable of resisting deterioration from the action of the gas or liquid which may be present in the process in which these tubes are utilized.

The cord-wound diffuser tube of the present invention is characterized by its adaptability to be fabricated in relatively long lengths which can be readily joined together into diffuser pipes of any desired length. This feature permits the tubes to be combined into a diffuser and air main. However, to accomplish the combining effect of an air main and diffuser, the rate of air feed along the length of the tube must be compensated for the loss of pressure along the diffusers due to the friction of flow. This compensation may be accomplished by either changing the orifice size along the diffusers, or by elevating the diffuser along its length so as to relieve the outside hydrostatic pressure in proportion to the frictional loss within the line. If the compensation is made by changing the orifice size along the length of the main, the com-

pensation is good for any rate of flow since both the orifice loss and the friction loss will vary together, that is to say, as the square of the rates of air feed.

If the compensation is made by elevating the far end of the diffuser main, and thus reducing the outside hydrostatic pressure, the compensation will only give uniform diffusion for one particular rate of air flow. This method has a very apparent advantage. As for example, if the air main or diffuser tube is so set that the loss of pressure is compensated at a low rate of air flow, there would then be a uniform rate of diffusion along the tank when a rate of air feed was low, and presumably when the sewage was weak, as at night. When the strength of the sewage and the desired rate of air flow increased, there would be more loss along the line which would mean that the head end of the tank would receive a greater proportion of the air flow. In other words, this arrangement would lead to tapered aeration during the high flow, and uniform aeration at night. This then would be an automatically modulated tapered aeration process.

An advantage of the diffuser tube of the present invention is its lightness of construction, which lends itself to be readily raised from the liquid in which it is immersed. The lightness in weight combined with the diffuser-air main feature, produces a construction that is inexpensive to manufacture and very simple in its installation.

In such an installation, the diffuser mains, one or more in spaced relation, as desired, would lie parallel to and adjacent the aeration tank wall. In a typical aeration tank of the activated sludge process of treating sewage, in a space of some 2 feet above the level of the diffuser main, mixing of the alternate bands of rising air bubbles and water and rising bands of solid water takes place. There is some advantage in placing the diffuser mains parallel to the tank wall because the lateral sweep of the water toward the wall effects thorough mixing and distribution somewhat more rapidly than would be the case where the tubes are perpendicular to the wall.

An important feature of the new diffuser tube is the uniformity of distribution of the gas or vapor across the length of the tube. It has been found that when air is being discharged through a diffuser tube at a non-uniform rate throughout its length, there are areas of excessive discharge which cause the air bubbles to coalesce in these areas. In consequence, the air is not uniformly dispersed throughout the liquid surrounding the tube, and the system does not operate at a maximum efficiency. With the diffuser tube of the present invention, the uniformity of air diffusion through each tube can be controlled very closely by the amount of compression and tension that is put upon the cord when wrapping around the hollow metal core, thus producing a very uniform diffusion and enabling the systems in which they are used to operate at a maximum efficiency.

A problem that has always been present when utilizing diffuser tubes is the matter of head loss. In the diffuser tube of my invention, the head loss is relatively low, due to the character and the very short length of the pores through which the air passes from the tube to the liquid.

The structures by which the various results

are attained will be described in connection with the accompanying drawings, in which:

Figure 1 is a fragmentary perspective view of an air main with a plurality of diffuser tubes embodying the invention extending therefrom;

Fig. 2 is an enlarged view of one of the diffuser tubes showing the twisted strand cord about the foraminated core, partly in elevation and partly in section;

Fig. 3 is a longitudinal sectional view taken along the line 3—3 of Fig. 2;

Fig. 4 is a cross sectional view taken along the line 4—4 of Fig. 3;

Fig. 5 is a highly magnified longitudinal sectional view taken along the line 5—5 of Fig. 4;

Fig. 6 is a greatly enlarged side elevational view of a mono-filament cord which may be used in accordance with the present invention;

Fig. 7 is a magnified longitudinal sectional view, similar to Fig. 5, showing the cross sectional configuration of the mono-filament cord;

Fig. 8 is an enlarged side elevational view of a modified form of diffuser tube having intermittent longitudinal flutings;

Fig. 8a is a longitudinal sectional view taken along the line 8a—8a of Fig. 8;

Fig. 9 is a view, partly in section and partly in elevation, showing an elongated modified form of diffuser tube;

Fig. 9a is a longitudinal sectional view taken along the line 9a—9a of Fig. 9;

Fig. 10 is a cross sectional view taken along the line 10—10 of Fig. 9;

Fig. 11 is a cross sectional view taken along the line 11—11 of Fig. 9;

Fig. 12 is a fragmentary longitudinal sectional view showing a plurality of diffuser cores joined together to form elongated units which are clamped together to form diffuser mains of any required length;

Fig. 13 is a cross sectional view taken along the line 13—13 of Fig. 12;

Fig. 14 is an enlarged fragmentary longitudinal sectional view showing the means for clamping together lengths of diffuser cores; and

Fig. 15 is a cross sectional view taken along the line 15—15 of Fig. 14.

In the drawings, the reference numeral 2 indicates an air main having a plurality of threaded openings 3 into each of which a diffuser tube 4 is screwed. The diffuser tube comprises a hollow core 5, of steel or other suitable material, depending upon the characteristics of the materials with which it is designed to come into contact with, a winding 6 of cord which covers the entire core, and a pair of end caps 7 and 8 which may be formed of the same material as the core. The core is an open ended cylindrical tube to the ends of which caps 7 and 8 are secured in any suitable manner, preferably by welding. End cap 7 has a pair of apertures 9 and 9' through which the starting end of cord winding 6 is threaded and knotted, as indicated at 10, to provide a firm anchor for the winding. End cap 8 has an exteriorly threaded neck 11 which fits into threaded opening 3 in the air main. A bolt 12 is threaded into end cap 8 to provide an anchor for the end of the cord winding. After the end of the cord is wrapped around the stem of the bolt 12 the bolt is screwed down to hold the cord securely.

Core 5 is fluted to provide alternate ridges 13 and valleys 14 extending longitudinally of the core. One or more orifices 15 are provided in each of the valleys for the passage of air or gas from the inside of the core through the winding.

The cord, which is in close contact with the ridges on the core, cooperates with each valley to form individual air spaces. The flow of air into these spaces is controlled by the orifices. Preferably one or two orifices are provided for each two feet of valley for more effective control.

The cord wound around the outside of the core may be formed of two or more strands of suitable material twisted into rope form. The preferred cord is formed of three strands of material twisted together as shown. The interstices between the twisted strands of cord when the latter is wound about the core form slanting pores through which the air which has passed from the inside of the core through orifices 15 passes in a diffused state from the pores into the surrounding liquid. The cross sectional area of these slanting pores can be accurately controlled by employing a cord of uniform, non-circular cross-section, winding it under uniform tension, and compressing the winding uniformly along the length of the tube.

In winding the cord on the core it is important to use only one layer of cord because the character and size of the path made by the interstices of the strands can thereby be accurately controlled by the compressive force used to squeeze the coils together. The addition of a second layer of cord causes the first layer to be flattened out somewhat and the accuracy of pore size control is lost. Furthermore, the head loss is greatly increased because the air must force its way through the pores of two layers, and the pores of the second layer are not necessarily a direct continuation of the pores of the first layer. This latter fact causes the diffusion to be uneven when two layers of cord are used. The increased head loss and the unevenness of the diffusion makes the use of tubes wound with two layers of cord prohibitively expensive.

The cord may be formed of any suitable material, textile or plastic, capable of withstanding the corrosive effects of the liquid with which it is to be brought in contact. A preferred material is a vinyl resin of the type commercially known as "Saran" which is formed from a copolymer of vinyl chloride and vinylidene chloride. It will be obvious that any number of strands, not less than two, may be used in forming the cord. The cross sectional configuration of the cord formed from three twisted strands of "Saran" is clearly shown in Fig. 5.

The cord may be a mono-filament of "Saran" or similar material, as shown at 16, in Figs. 6 and 7. This cord is formed by extrusion of the plastic while in a thermoplastic state with a plurality of helical grooves 17 (here shown with three grooves) extending longitudinally of the cord. If desired, the grooves may be straight and the cord twisted as it is wound around the core. In either case the paths formed by the grooves can be controlled as in the case of the multi-strand cord so that the diffusion of the air is substantially uniform throughout the length of the tube.

The use of a cord of non-circular cross section, as exemplified by both the multi-strand cord shown in Fig. 5 and the mono-filament cord shown in Fig. 7, is of particular importance because it is this non-circular shape that causes the formation of tortuous paths that are small enough to cause diffusion of the air passing therethrough. The advantages of the non-circular cross sectional area can best be appreciated by comparison of the results attained with those

attained by wrapping wire of circular cross section around a similar core. With the latter structure the air passages formed between adjacent convolutions of wire may be regular, but they are very long in comparison to their widths, and are essentially continuous slits. Much larger bubbles are emitted from a long slit than from a series of pores of equal area, with the result that coalescence occurs. The cord of non-circular cross-section used in accordance with the present invention forms pores of substantially circular or elliptical cross section so spaced apart that the streams of bubbles emitted by them do not coalesce.

In Figs. 8 and 8a a modified form of diffuser tube 18 is shown in which a plurality of intermittently spaced depressions 19 extending longitudinally of the diffuser are provided by embossing or otherwise forming the core. Orifices 20, similar to orifices 15 are provided in the bottom of each depression and end caps 7' and 8' are provided to close the ends as in the case of the diffuser of Fig. 2. The core may be covered with a single winding of cord, which may be either multi-strand or mono-filament, as described above.

The diffuser 21, illustrated in Fig. 9, differs from that shown in Fig. 8 only in that it is of greater length. The increased length may be obtained by forming a longer core with intermediate circumferential stiffening ribs 22 or by welding together a plurality of shorter cores. End caps 23 and 24, similar to end caps 7 and 8, respectively, are secured to opposite ends of diffuser 21. The cord 25 may be wound continuously around the entire length of the core, but it is preferred to wind the cord in separate lengths with the starting end secured to end cap 23 as described in connection with Figs. 2 and 3, in the case of the length adjacent that end, and to the ribs 22 by a knot 26 (Fig. 9a), in the case of the succeeding lengths. The other end of the cord for each core section is secured to the stiffening rib at the end of each section except the last section, and to end cap 24 in the case of the last section, as by bolt 27.

In the embodiment of the invention shown in Figs. 12 to 15, there is shown an air diffuser pipe 28. This pipe comprises a plurality of sections bolted together as shown in Figs. 12 and 14. A washer or sealing gasket 30 is positioned between the ends of adjacent sections. Brackets 31 each comprise an inverted U-shaped portion 32 and two oppositely directed flanges 33 parallel to the surface of the pipe sections, which are secured adjacent each end of each section by welding, as shown in Fig. 15. Clamping bolts 34 pass through brackets 31 on adjacent pipe sections and secure the sections together. Each pipe section comprises a plurality of smaller sections welded together at their ends, as indicated at 35, Fig. 12. Each pipe section is fluted, the valleys provided with orifices and the ridges covered by a single layer of cord, as described above.

From the foregoing it will be seen that I have devised a new and improved diffuser in which the diffusion of air or gas therethrough can be regulated with great accuracy. The diffuser pipe may be fabricated in any desirable length. While I have described a few preferred embodiments of my invention in considerable detail it will be understood that the description is intended to be illustrative, rather than restrictive, as many details may be modified or changed without departing from the spirit or scope of the invention. Ac-

cordingly, I do not intend to be restricted to the exact structures described, except as limited by the appended claims.

I claim:

1. A diffuser tube comprising a hollow core having an inlet for air or a gas, a plurality of orifices in said core, a covering of compressible monofilament cord coiled tightly around said core with the coils pressed tightly together, and means to hold said cord on said core in the said tightly pressed condition, said cord having a plurality of helical grooves extending longitudinally in substantially parallel relationship, whereby the interstices between adjacent convolutions of said cord form substantially uniform pores for the emission of an aeriform body passing through said orifices.

2. A diffuser tube comprising a perforated hollow core having an inlet for air or a gas, and a single layer of compressible cord coiled tightly around said core with the coils pressed tightly together and with the compressed sides of adjacent convolutions of said cord in contact with each other, said cord having a plurality of helical grooves extending longitudinally in substantially parallel relationship, whereby the interstices between adjacent convolutions of said cord form substantially uniform pores for the emission of air passing through said orifices, and means to hold said cord about said core in the aforesaid tightly coiled state.

3. A diffuser tube comprising a perforated hollow core having an inlet for air or a gas, and a single layer of compressible cord coiled tightly around said core with the coils pressed tightly together and with the compressed sides of adjacent convolutions of said cord in contact with each other, said cord having a non-circular cross section formed by a plurality of helical grooves extending longitudinally in substantially parallel relationship, whereby the interstices between adjacent convolutions of said cord form substantially uniform pores for the emission of air passing through said orifices, and means to hold said cord about said core in the aforesaid tightly coiled state.

4. A diffuser tube comprising a perforated hollow core having an inlet for air or a gas, and a twisted, multi-strand, compressible cord coiled tightly around said core in a single layer with the coils pressed tightly together and with the compressed sides of adjacent convolutions of said cord in contact with each other, whereby the interstices between adjacent convolutions of said cord form substantially uniform pores for the emission of air passing through said orifices, and means to hold said cord about said core in the aforesaid tightly coiled state.

5. A diffuser tube comprising a plurality of core sections each of which has an inlet for air or a gas and each of which is perforated for the passage of said aeriform body, said core sections being secured together in end to end relationship, and a single layer of compressible cord wrapped tightly around each of said sections with the coils pressed tightly together and with the compressed sides of adjacent convolutions of said cord on each of said sections in contact with each other, the cord on each of said sections having a plurality of helical grooves extending longitudinally in substantially parallel relationship, whereby the interstices between adjacent convolutions of said cord form substantially uniform pores for the emission of air passing

through said perforations, and means to hold the cord of each of said sections about said sections in the aforesaid tightly coiled state.

6. A diffuser tube comprising a plurality of core sections each of which has an inlet for air or a gas and each of which is perforated for the passage of said aeriform body, said core sections being secured together in end to end relationship, and a single layer of a twisted, multi-strand compressible cord coiled tightly around each of said sections with the coils pressed tightly together and with the compressed sides of adjacent convolutions of said cord on each of said sections in contact with each other, whereby the interstices between adjacent convolutions of said cord from substantially uniform pores for the emission of air passing through said perforations, and means to hold said cord about each of said sections in the aforesaid tightly coiled state.

20 7. A diffuser tube comprising a hollow core having an inlet for air or a gas, said core being fluted to form ridges and valleys extending longitudinally of said core, each of said valleys having an orifice for the passage of an aeriform body 25 from inside said core, and a single layer of compressible cord wound tightly around said core with the coils pressed tightly together and with the compressed sides of adjacent convolutions of said cord in contact with each other, said cord 30 having a non-circular cross section formed by a plurality of helical grooves extending longitudinally in substantially parallel relationship, whereby the interstices between adjacent convolutions of said cord form substantially uniform pores for the emission of an aeriform body passing through said orifices, and means to hold said cord about said core in the aforesaid tightly coiled state.

35 8. A diffuser tube comprising a hollow core having an inlet for air or a gas, said core having portions of its exterior surface depressed relative to the rest of said core, orifices extending through said depressed portions, and a single 40 layer of compressible cord wound tightly around said core with the coils pressed tightly together and with the compressed sides of adjacent convolutions of said cord in contact with each other, said cord having a non-circular cross section formed by a plurality of helical grooves extending longitudinally in substantially parallel relationship, whereby the interstices between adjacent convolutions of said cord form substantially uniform pores for the emission of an aeriform body passing through said orifices, and means to hold said cord about said core in the 45 aforesaid tightly coiled state.
